UNITED STATES PATENT OFFICE.

EDWARD BRETCH, OF ST. LOUIS, MISSOURI.

SHORT-CIRCUITING DEVICE.

1,111,358.

Specification of Letters Patent. Patented Sept. 22, 1914.

Application filed February 14, 1914. Serial No. 818,674.

To all whom it may concern:

Be it known that I, EDWARD BRETCH, a citizen of the United States, residing at the city of St. Louis, State of Missouri, have invented a certain new and useful Improvement in Short-Circuiting Devices, of which the following is a full, clear, and exact description, such as will enable others skilled in the art to which it appertains to make and use the same, reference being had to the accompanying drawings, forming part of this specification, in which—

Figure 1 is a vertical section through a motor equipped with my improved short circuiting device. Fig. 2 is a side view of a motor partly in section showing the commutator and short circuiting device in elevation. Fig. 3 is a detail illustrating the relationship of parts when a short circuiting plate is in position to short-circuit the armature.

My invention relates to improvements in a short circuiting device for alternating current motors having a series starting characteristic and designed to be short-circuited when the motor has reached its running speed.

The object of my invention is to improve generally upon the construction of such devices with the idea of simplifying their construction and securing a more positive action, and a better rubbing contact.

With these and other objects in view, which will be obvious, it will be understood by reference to the drawings that 1 represents the motor casing, 2 the armature shaft, and 4 the armature. Mounted on the shaft 2 is a collar 5 which is designed to support the commutator segments 6, the same being clamped thereon by the clamping ring 7 which is adjustable by means of the bolts 8.

Slidable longitudinally on the shaft is a short circuiting ring 9 which is provided with an annular ridge 10 forming a mounting and a fulcrum for the short circuiting plates 11. These short circuiting plates 11 are of a general L-shape having a transversely extending arm provided with a hooked end adapted to engage the ridge 10, and a comparatively heavy arm extending radially of the shaft and formed with a contact making portion 11a. A spring 12 bearing at one end against the short circuiting ring 9 and at the other against a nut or stop member 14, tends to press ring 9 inwardly and hold the short circuiting plates 11 re-

tracted against stop ring 14. When short circuiting plates 11 are in this position, they are out of contact with the commutator segments 6 and the various segments with their related armature windings are independent. This is the starting position of the short circuiting plates 11, and, with the plates in this position the motor is adapted to start as a repulsion motor. When the armature shaft shall have attained sufficient speed so that the force of the centrifugal tendency of the plates 11 will overcome the power of spring 12, the outer ends of the plates 11 will move out radially from the shaft, drawing the ring 9 outwardly against the tension of spring 12. In this position, the contact making portions 11a of the short circuiting plates will engage the ends of the commutator segments 6 and short-circuit the segments and the armature windings through the plates 11 and the ring 9. The general operation of short-circuiting a motor in this fashion is well known in the art, but the particular form and arrangement of my short circuiting plates renders the device illustrated particularly efficient and an improvement upon the devices heretofore employed. Because of the L-shape of the plates 11 and the disposal of ring 9 and the commutator segments 6, a very heavy contact pressure between the plates 11 and segments 6 is secured. This is due to the fact that, the spring 12 acting in a direction longitudinally of the shaft, and the centrifugal force acting on the plates in a direction radially of the shaft and at substantially right angles to the force of the spring, the resulting pull on the outer extremities of the plates 11 is directly against the ends of the commutator segments. The line of this pull is illustrated by the dotted line in Fig. 3. This function is secured by having the fulcrum point and the contact point of the segments disposed in such relationship to each other that a line from one to the other intersects the commutator segments when the plates are in operating position.

A further advantage of the device as constructed lies in the fact that there is a leverage of considerable length between the power end of the plates, represented by their heavy radial arms, and their fulcrum end. This renders the plates more responsive to the centrifugal influence, and disposes most of their weight where it is most efficient. This construction also provides the rubbing

contact on a vertical face of the commutator, and thereby provides an added assurance against sparking and bad contact as the vertical face does not afford a resting place 5 for dirt.

What I claim is:

1. In an electric motor, a centrifugal short circuiting device comprising the combination of an armature shaft, commutator segments carried thereon, and having contact faces disposed normal to the shaft, and short circuiting plates carried on said shaft and adapted to coöperate with said commutator segments; said short circuiting plates being 10 of general L-shape and each having one arm directed longitudinally of said shaft and the other arm radially of said shaft, said first mentioned arm being fulcrumed on a member movable longitudinally of the shaft and 15 said radial arm being adapted to coöperate with a contact face of a commutator segment.
2. In a motor, a centrifugal short circuiting device comprising the combination of 20 commutator segments carried by the shaft, and having contact faces disposed normal thereto, a short circuiting member movable longitudinally on the shaft between the same and the commutator segments, a plurality of short circuiting plates each fulcrumed at one end on said short circuiting member and having its free end adapted to coöperate with a face of a commutator segment lying normal to the shaft, and a yielding 25 pressure means coöperating with said short circuiting member and tending to move the same in a direction away from the free ends of said short circuiting plates.
3. In an electric motor, a short circuiting 30 device comprising the combination of a revoluble shaft, short circuiting plates carried by said shaft and each fulcrumed at one

end to a short circuiting member movable longitudinally on said shaft, the other end of each of said short circuiting plates being 45 adapted to swing radially from said shaft under centrifugal influence, commutator segments carried by said shaft and having faces extending transversely of said shaft intermediate the extremities of said short circuiting plates, and yielding pressure means tending to move said short circuiting plates on said shaft in a direction opposite their free ends; said free ends of the short circuiting plates being adapted to coöperate 50 with the transversely disposed faces of said commutator segments.

4. In an electric motor, a short circuiting device comprising the combination of a revoluble shaft, commutator segments carried thereon, short circuiting plates carried on said shaft and each fulcrumed at one end radially nearer the shaft than the commutator segments, the other end of each of said short circuiting plates being adapted to 55 move away from said shaft, said commutator segments having faces disposed transversely of said shaft and positioned intermediate the longitudinal extremities of said short circuiting plates and adapted to coöperate 60 with the free ends of said short circuiting plates, and yielding pressure means operable upon the fulcrumed ends of said short circuiting plates to hold the free ends thereof in contact with the commutator segments 65 when said ends are swung away from said shaft.

In testimony whereof I hereunto affix my signature in the presence of two witnesses, this 12th day of February, 1914.

EDWARD BRETH.
